(57) **CLAIM**

I claim the ornamental design for an LED light, as shown and described.

DESCRIPTION

FIG. 1 is a front perspective view of the design of an LED light;

FIG. 2 is a back perspective view thereof;

FIG. 3 is a front elevation view thereof;

FIG. 4 is a back elevation view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of an LED light in which the design is embodied that form no part of the ornamental design.
